(57) CLAIM

The ornamental design for a watch case, as shown and described.

DESCRIPTION

FIG. 1 is a top and side perspective view of a watch case showing my new design;

FIG. 2 is a view similar to FIG. 1 but with the watch case rotated about a vertical axis;

FIG. 3 is a top plan view thereof;

FIG. 4 is a bottom plan view thereof;

FIG. 5 is a view thereof from the top of FIG. 3;

FIG. 6 is a view thereof from the bottom of FIG. 3;

FIG. 7 is a view thereof from the right of FIG. 3, a view thereof from the left of FIG. 3 being identical thereto; and, FIGS. 8-14 are views similar to FIGS. 1-7, respectively, but showing a second embodiment of my new design.
